Primary Examiner—Ruth McInroy(74) *Attorney, Agent, or Firm*—Brinks Hofer Gilson & Lione**CLAIM**

I claim the ornamental design for a front portion of a microwave oven, as shown and described.

DESCRIPTION

FIG. 1 is a top perspective view of a front portion of a microwave oven of the present invention;

FIG. 2 is a front view thereof; and,

FIG. 3 is a cross-sectional view along line 3—3 in FIG. 2. The ornamental design which is claimed is shown in solid lines in the drawings. Any broken lines in the drawings are for illustrative purposes only and form no part of the claimed design.
